INVENTOR

By Victor J. Evans

ATTORNEY

UNITED STATES PATENT OFFICE

FRED D. WARREN, OF CHICAGO, ILLINOIS

NAIL-CLEANING DEVICE

Application filed March 30, 1928. Serial No. 266,029.

This invention relates to certain novel improvements in nail cleaning devices and consists in the novel combination and arrangement of parts hereinafter described and 5 claimed.

It is an object of my invention to provide a device of the above named character which will be arranged so as to embody the bristle structure and which will be so arranged that 10 the bristles will be retained between the convolutions of a suitably twisted resilient member.

Another object of the invention is to provide means for holding the above described 15 bristle retaining means and said means is preferably arranged so as to permit expeditious holding thereof on one of the user's hands when the user is cleaning the finger nails on the other of his hands.

20 A further object of the invention is to arrange the device of the above named character in such a manner that the bristle structure may be expeditiously replaced when the same becomes worn.

25 Other objects will appear hereinafter.

The invention consists in the novel combination and arrangement of parts to be hereinafter described and claimed.

The invention will be best understood by 30 reference to the accompanying drawings, showing the preferred form of construction and in which:

Fig. 1 is a perspective elevational view depicting one embodiment of a preferred form 35 of construction for my invention;

Fig. 2 is a sectional detail view taken substantially on the line 2-2 on Fig. 1;

Fig. 3 is a perspective detail view depicting the particular formation of the cleaning 40 bristle construction and mounting;

Fig. 4 is a view depicting a modified form of construction over that disclosed in Fig. 1; and

Fig. 5 is an enlarged detail view disclosing 45 one end of the device as disclosed in Fig. 4.

In the drawings and more particularly Figs. 1 to 3 inclusive, I show a body portion 10 which includes downwardly extending lugs 11 and 12. The upper surface 13 of the 50 body portion 10 and the sides 14 and 15 are

preferably made concave in order that a user of the device may lay one of his fingers along the edge 13 and place the adjoining fingers along the edges 15 and 14. It is apparent that since these edges are concave, the user 55 may lay one finger along the edge 10 and the adjoining finger along either of the edges 14 or 15 and still very effectively retain the device.

Extending upwardly from the lower ends 60 of the lugs 11 and 12 are slots 16 and 17 which preferably have retaining lugs 18 (Fig. 2) formed adjacent their lower edge so as to prevent displacement of the cleaning member which is to be removably mounted therein. 65 The cleaning member includes bristles 19 which are adapted to be retained between the convolutions of the twisted members 20 and 21 as best depicted in Fig. 3. Adjacent the ends of the members 20 and 21, in juxtaposition to the ends of the bristles 19, said members 20 and 21 are disposed to embody parallelly extending portions 22 and 23 and the ends of the members 20 and 21 terminate in knot or humped portions 24 and 25. 70

In assembling the device the portion 22 is forced past the retaining lugs 18 into the notch 16 and the portion 23 is forced past the retaining lugs 18 in the slot 17 and thus the structure is held against displacement 80 from the body portion 10. The user then grips the device in the manner heretofore described and by moving the bristles 19 across the nails, dirt and other foreign matter may be removed from underneath said 85 nails. The members 20 and 21 are preferably formed of a material which embodies sufficient innate resiliency as to permit the bristle structure 19 to be yieldable.

In Figs. 4 and 5 I have depicted a construction wherein the members 20 and 21 are twisted so as to retain bristles 19 between the convolutions thereof. In this instance, however, the members 20 and 21 terminate in loops 26 and 27 as is clearly shown in Fig. 95 5. To the loops 26 and 27, rings 28 and 29 are secured which when the device is in use are adapted to be mounted on the fingers on one of the user's hands as depicted in Fig. 4.

I have shown the body 10 as embodying a 100

recess 30 which extends therein from one end thereof and a removable cap 31 is provided which is adapted to close the open end of said recess. This recess is adapted to serve as a storage chamber for the cleaning members comprised of members 20 and 21 and the bristles, 19.

It is apparent from the foregoing description that I have provided an economical and simple construction which will permit expeditious gripping of the device by the user. Inasmuch as the members 20 and 21 are yieldable, it is apparent that they will conform to the shape of the tips of the user's fingers so as to facilitate the cleaning thereof.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. In a brush structure, a body member having lugs extending outwardly from one face thereof, said body having a longitudinal groove formed in the opposite face thereof and having the side walls thereof curved to form the ends of said lugs narrower than said opposite face, said lugs having slots extending therein from the outer ends thereof, two innately resilient intertwined members having bristles retained in the convolutions thereof, said intertwined members having portions adapted to be frictionally arranged in said slots, said body having an opening formed therein adapted to extend parallel to said longitudinal groove to provide a storage chamber, and means for closing the open end of said chamber.
2. In a nail cleaning device, two intertwined innately resilient members, bristles retained between the convolutions of said members, said twisted members terminating in flattened portions, a relatively elongated body member having lugs depending from the ends thereof, said lugs having slots formed therein adapted to frictionally receive the flattened portion on said intertwined members, said body member having an opening formed therein adapted to extend from one end thereof to provide a storage chamber, and means for closing the open end of said opening.

60 In testimony whereof I affix my signature.
FRED D. WARREN.
